UNITED STATES PATENT OFFICE

2,382,888

THERMOCOUPLE MOUNTING FOR
FURNACES

William B. Levy, Wilmington, Del.

Application January 23, 1943, Serial No. 473,380

4 Claims.

(Cl. 285—47)

This invention relates to metal-heating furnaces; and more particularly to furnaces of the muffle type, as disclosed in United States Letters Patent, No. 2,277,595, issued March 24, 1942, to William B. Levy (the present applicant) and Sylvan N. Levy, as joint inventors.

The present invention is directed to an improved form of mounting for the thermo-couple currently employed in the aforesaid type of furnace instead of the mounting disclosed in the aforesaid patent.

In the accompanying drawing:

Fig. 1 is a fragmentary sectional elevation showing the mounting in detail; and

Fig. 2 illustrates a modified form of mounting.

The aforesaid type of furnace normally includes a metallic shell composed, principally, of a cylindrical body, a front plate, and a back plate 4, suitably secured together to provide an integral structure.

The shell 1 houses a body of heat-insulating material 5, in the center of which is located the combustion chamber of the furnace, the front and back plates of which support the muffle of the furnace.

The muffle is heated by a swirling sheet of flame revolving about the axis of the muffle, externally thereof, within the combustion chamber, as disclosed in the aforesaid patent. Atmosphere for treating the work specimens being heated in the muffle is supplied thereto through a port formed by a tube extending through the back wall of the furnace.

Heretofore, the temperature of the interior of the muffle has been constantly determined and registered by use of a thermo-couple device projecting through the back wall 13 of the furnace and the back wall 18 of the muffle, with the inner end of the thermo-couple device projecting axially of and into the muffle a predetermined distance from the back wall 18 thereof.

As shown more particularly in Fig. 1, the thermo-couple device 20 is of a commercially obtainable type and includes a ceramic tube 21, composed of sillimanite, porcelain, etc. within which is located the couple, in the form of one or more relatively fine gauge wires (not shown). The free end 22 of the tube 21 is closed to seal the thermo-sensitive element therein. The opposite end 23 of the tube 21 snugly fits into one end of a tapering, externally threaded standard pipe bushing 24, and is firmly secured therein. Threaded into the opposite end of the bushing 24 is the neck portion 25a of the base 25 of the thermo-couple device, in which latter are housed

the mechanical and/or electrical terminals of the couple, to which the thermo-sensitive wires are connected.

The present invention is not concerned with the detail structure of the thermo-couple device 20, except in so far as the device 20 includes the metallic base 25, the bushing 24 which serves as a shank for said base, and the ceramic tube 21 projecting from and axially therewith, with the long thin body portion of the tube extending beyond the screw threaded bushing 24 which constitutes the terminal end or shank of the metal base structure 25.

Heretofore, the thermo-couple device 20 has been inserted through a hole 26 formed in the insulating material 5 in the back wall 13 of the furnace, and through an axially aligned hole 27 formed in the back wall 18 of the muffle. The back plate 4 of the furnace normally was provided with a screw threaded opening 28, into which the tapered bushing 24 of the base 25 of the thermo-couple device 20 was screwed, by means of a wrench applied directly to a hexagonal portion 29 of the bushing 24.

The above noted structure was satisfactory when the thermo-couple device was being initially applied to the assembled furnace, i. e., before operation of the furnace. During subsequent use of the furnace, which operates at temperatures ranging as high as 2500° F., the tube 21, in many instances, became warped or cracked cross-sectionally. In most instances, the opening 27 around the tube 21 is closed and sealed with a refractory insulation which hardens under the high operating temperatures of the furnace and holds the tube securely in the furnace wall.

If at any time after installation, it became necessary, for any reason whatsoever, to remove the thermo-couple device 20 from the furnace, rotation of the device as a unit was necessary, by applying a wrench to the hexagonal portion 29 thereof, in order to back the bushing 24 out of the threaded opening 28 in the back plate 4 of the furnace, consequently any axial deformation or misalignment of the tube 21, as the tube was rotated within the openings 26 and 27, caused the tube 21 and the thermo-sensitive wires within the tube to break, rendering the couple useless.

The object of the present invention is to eliminate all necessity for rotating the device 20 in a furnace wall during either the inserting of the device 20 in a furnace or the removal thereof from a furnace; and to eliminate all necessity for applying a wrench to any part of the couple at

any time after the device 20 has been initially prepared to be installed in a furnace.

According to the present invention, the thermo-couple device 20 is removed from the furnace by a straight axial movement of the tube 21 through the openings 26 and 27, without rotating the tube 21 of the thermo-couple within these openings.

For the purpose of fulfilling the object of the invention, the tapered threaded bushing 24 of the base 25 of the device 20 is first threaded into an internally threaded boss 30 of a thread-section of a standard pipe union 31, which section also includes external threads for cooperation with the internal threads of the ring or nut section of the union. This assembly may be made at any place remote to the furnace.

Into the threaded opening 28, in the back plate 4 of the furnace, is threaded one end of a standard pipe nipple 32. The opposite end of the nipple 32 is threaded into the internal threads of the boss 33 of the second or shoulder-section of the union 31, which is provided with an annular stepped flange 34 about which is adapted to revolve the nut or ring section 35 of the union 31.

After the nipple 32, with the shoulder-section 33 secured thereto, and with the ring section 35 of the union 31 loosely mounted thereon, is installed in the tapped hole 28 formed in the back wall 13 of the furnace, the thermo-couple device 20 is then put in place, by inserting the tube 21 axially through the bore of the nipple 32, the hole 26 in the insulation 5, and the hole 27 in the rear wall 18 of the muffle 11, all of which are in axial alignment with each other.

The externally threaded flange 36 of the thread-section 30 of the union 31, which has been previously screwed onto the threaded bushing 24 of the couple device 20, is then brought into axially abutting relation to the shouldered flange section 33 of the union, whereupon the nut section 35 of the union 31 is screwed onto the peripheral threads of the flange 36 of the thread-section 30 of the union 31, until a tight joint is formed between these elements, said nut being so arranged as to be rotated about the aligned elements 30 and 33 of the union without necessitating the rotation of either of these elements or the thermo-couple device 20 carried by the element 30 of the union.

The thermo-couple device 20 may be removed from the furnace by reversing the order above recited, i. e., by merely loosening and backing off the nut 35 from the couple-carrying element 30, whereupon the tube 21 may be carefully withdrawn, in a straight line, from the holes 26 and 27 and the nipple 32, without danger of breaking said tube 21, or the wires therein in instances where the tube has been cracked cross-sectionally.

From the foregoing it will be clear that a standard flange-type union may be used in place of the screw-type previously described, as shown in Fig. 2. In this instance, one section of a flange union 30a may be threaded onto the projecting end of the nipple 32, and the other section 33a threaded onto the bushing 24 of the thermo-couple device 20, whereupon the two flanged sections may be secured together by bolts 35a. The procedure in inserting and withdrawing the thermo-couple will be substantially the same in this case as in the case of the mounting shown in Fig. 1.

From the above, it will be clear that a thoroughly practical and highly improved detachable

mounting for the thermo-couple device may be provided by the use of ordinary standard pipe unions and nipples, at very low cost.

It will also be clear that in removing a thermo-couple device from a furnace, when provided with the improved mounting of the present invention, the tube may be gently removed from the furnace wall by careful manual manipulation, in a straight line, once the elements of the mounting have been disconnected, under the remover's sense of touch by which the pressure applied to the tube may be delicately controlled and the tube, or wires in the tube, will be spared from breakage, which would be impossible under the prior art practices.

I claim:

1. In a furnace comprising a combustion chamber and a back wall including an exterior metal plate and having an opening extending from the exterior of said wall to the interior of

20 said combustion chamber for passage of an axially elongated member of a thermo-couple device including a base structure provided with a shank adjacent the juncture of the elongated member therewith; the improvement which comprises a

25 multi-sectional mounting for said thermo-couple device including one section stably connected to the exterior plate of said wall at the outer end solely of said opening, a section stably secured to said shank, and means for securing 30 said sections together to afford axial non-rotational movement of said elongated member through said opening in applying said thermo-couple device to and removing it from said furnace.

35 2. In a furnace comprising a combustion chamber and a back wall including an exterior metal plate and having an opening extending from the exterior of said wall to the interior of

40 said combustion chamber for passage of an axially elongated member of a thermo-couple device including a base structure provided with an externally threaded shank adjacent the juncture of the elongated member therewith, said back wall having a threaded mouth extending through

45 said exterior plate thereof at the outer end of said opening for normally receiving said shank; the improvement which consists of a multi-sectional mounting for said thermo-couple device including one section having an externally

50 threaded projection screwed into said mouth through said plate, a second section threaded onto said shank, and means for securing said sections together to afford axial non-rotational movement of said elongated member through 55 said opening and the first said section of the mounting in applying the thermo-couple device to and in removing it from said furnace.

3. In a furnace comprising a combustion chamber and a back wall including an exterior

60 metal plate and having an opening extending from the exterior of said wall to the interior of said combustion chamber for passage of an axially elongated member of a thermo-couple device including a base structure provided with an

65 externally threaded shank adjacent the juncture of the elongated member therewith, said back wall having a threaded mouth extending through said exterior plate thereof at the outer end of

70 said opening for normally receiving said shank; the improvement which consists of a multi-sectional mounting for said thermo-couple device including a nipple screwed into said mouth through said plate, a section threaded onto said nipple, a section threaded onto said shank, and means for securing said sections together to af-

ford axial non-rotational movement of said elongated member through said opening said nipple and said first section in applying the thermo-couple device to and in removing it from said furnace.

4. In a furnace comprising a combustion chamber and a back wall including an exterior metal plate and having an opening extending from the exterior of said wall to the interior of said combustion chamber for passage of an axially elongated member of a thermo-couple device including a base structure provided with an externally threaded shank adjacent the juncture of the elongated member therewith, said back wall having a threaded mouth extending through 15 said exterior plate thereof at the outer end of

said opening for normally receiving said shank; the improvement which consists of a multi-sectional mounting for said thermo-couple device including a nipple screwed into said mouth 5 through said plate, a section threaded onto said nipple, a section threaded onto said shank, and a ring nut rotatably mounted on one of said sections and having threaded engagement with the other of said sections for securing said sections together to afford axial non-rotational movement of said elongated member through said opening said nipple and said first section in applying the thermo-couple device to and in removing it from said furnace.
